CLAIM

The ornamental design for a control device, as shown and described.

DESCRIPTION

FIG. 1 is a perspective view of a control device showing our new design.

FIG. 2 is a front view thereof.

FIG. 3 is a left side view thereof.

FIG. 4 is a right side view thereof.

FIG. 5 is a top view thereof.

FIG. 6 is a bottom view thereof.

FIG. 7 is a perspective view of a control device according to a second embodiment of our new design.

FIG. 8 is a front view thereof.

FIG. 9 is a left side view thereof.

FIG. 10 is a right side view thereof.

FIG. 11 is a top view thereof; and,

FIG. 12 is a bottom view thereof.

The rear views form no part of the design and are omitted. The oblique shade lines shown in the drawings indicate a transparent or translucent surface. The portions of the drawings appearing in broken lines are for environment only and do not form part of the claimed design.

The disclosure of the ornamental design shown in the accompanying drawings herein includes embodiments in which one or more of the elements depicted in solid lines may be reduced to broken lines.
